US00D964955S

(12) **United States Design Patent** (10) Patent No.: **US D964,955 S**
(45) Date of Patent: **** Sep. 27, 2022**

(54) **MOBILE PHONE**

(71) Applicant: **Samsung Electronics Co., Ltd.**, Suwon-si (KR)

(72) Inventors: **Minsoo Kwon**, Seoul (KR); **Eun Sun Chae**, Seoul (KR); **Aejung Seo**, Seoul (KR)

(73) Assignee: **SAMSUNG ELECTRONICS CO., LTD.**, Suwon-si (KR)

(**) Term: **15 Years**

(21) Appl. No.: **29/736,838**

(22) Filed: **Jun. 3, 2020**

Related U.S. Application Data

(60) Continuation of application No. 29/710,304, filed on Oct. 22, 2019, now Pat. No. Des. 900,775, which is a (Continued)

(57) **CLAIM**

The ornamental design for a mobile phone, as shown and described.

DESCRIPTION

FIG. 1 is a front perspective view of a mobile phone showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the figures depict portions of the mobile phone that form no part of the claimed design.

1 Claim, 5 Drawing Sheets

Related U.S. Application Data

continuation of application No. 29/689,775, filed on May 1, 2019, now Pat. No. Des. 916,806, which is a division of application No. 29/613,433, filed on Aug. 10, 2017, now Pat. No. Des. 864,226.

(58) Field of Classification Search

CPC ... H04M 1/0202; H04M 1/0266; H04M 1/027
See application file for complete search history.
